J. CARRICART

TOOL FOR COMPRESSING AND INSERTING VALVE SPRINGS

Filed Dec. 9, 1920

INVENTOR.
John Carricart
BY *Frederick D. Hayes*
ATTORNEY

UNITED STATES PATENT OFFICE.

JOHN CARRICART, OF SANTA BARBARA, CALIFORNIA.

TOOL FOR COMPRESSING AND INSERTING VALVE SPRINGS.

Application filed December 9, 1920. Serial No. 429,361.

To all whom it may concern:

Be it known that I, JOHN CARRICART, a citizen of the United States, and a resident of Santa Barbara, in the county of Santa Barbara and State of California, have invented certain new and useful Improvements in Tools for Compressing and Inserting Valve Springs, of which the following is a specification.

10 This invention relates to a tool which is constructed for compressing springs and by the use of which the springs thus compressed can be removed in compressed condition from the compressing means and inserted in the places in which they are to function. For example, if the springs are those employed in closing engine valves, the tool is of service in inserting the compressed springs in place in the engine.

20 Springs having as high an expansive pressure as ninety pounds are at present employed for closing the valves of many of the larger types of automobile engines and, though it is not so difficult a matter to remove the springs, the replacing of the springs of the larger engines in their functioning positions is at present so difficult and troublesome that the valves of such engines are usually ground with the springs 25 in place instead of with the springs removed, as is preferable.

An object of the invention is to produce a tool of this character of comparatively simple construction and one that is easily operated.

Another object is to so construct the tool that the spring transferring member can be readily placed upon the spring in the compressing means and, upon release of the spring by the compressing means, can be easily removed holding the spring in its grip.

The accompanying drawings illustrate the invention:

25 Figure 1 is a side view of a tool embodying the invention, a spring being shown in compressed condition in the tool;

Figure 2 is a sectional elevation on line indicated by x^2-x^2 , Figure 1;

30 Figure 3 is a plan section on line indicated by x^3-x^3 , Figure 1;

Figure 4 is a plan view of Figure 1; and

Figure 5 is a perspective view of the spring transferring member, showing it holding a compressed spring ready for in-

sertion of the spring in the position in which it functions.

There are provided a stationary jaw 1 and a movable jaw 2, the movable jaw being moved toward and from the stationary jaw 00 by suitable means such as a screw 3 that adjustably engages a lug 4 forming one end of the tool body 5. The jaw 1 forms the opposite end of the body 5. The body 5 may be of any desired shape, and in the present 05 instance is channel- or V-shape, as clearly shown in Figure 3, and the jaw 2 has a V-shaped portion 6 adapted to slidably fit the channel. The unthreaded portion 7 of the screw 3 rotates in the jaw 2 when the 10 screw is turned. The screw 3 is provided with a handle 8 whereby it may be readily turned by the operator to advance or retract the jaw 2.

The spring to be compressed is placed between the jaws 1, 2, when the jaw 2 is in its retracted position adjacent the lug 4. Such a spring is indicated at A in the drawings in the compressed condition, since the screw 3 has been rotated to move the jaw 2 toward 15 the jaw 1.

When the spring A has thus been compressed, a spring-transferring member 9 is adapted to be placed on the spring A. The spring-inserting member comprises a U- 20 shape handle 10 and gripping members, each of which in turn comprises arms 11 extending normal to the plane of the handle 10 and jaws 12 at opposite ends of the arms 11. Preferably the handle 10 is more or less re- 25

silient so as to yieldingly hold the arms 11 toward each other. In practice, the spring will be compressed so that it is slightly shorter than the distance between the opposed jaws 12 of the arms 11, preferably 30 until adjacent coils touch each other, and then the spring transferring member will be slipped over the ends of the spring so that a line passing through the jaws 12 of the opposed arms will pass through the axis of the 35 spring. Owing to the resilient character of the handle 10 the arms 11 will be clamped against the opposite sides of the spring, so that the spring-transferring member will be retained in position without the operator 40 holding it. When the spring-transferring member has been thus positioned, the operator will turn the screw 3 so as to retract the 45 jaw 2, thus permitting the spring to expand sufficiently to engage the jaws 12 and be 50

loose between the jaws 1, 2. The operator will then grasp the handle 10 and withdraw the spring, by the aid thereof, from between the jaws 1, 2. The spring-transferring member, with the compressed spring held thereby, is clearly shown in Figure 5 of the drawings. The operator may now place the spring in position between the valve stem head and the spring seat of an engine, or in any other position that the spring belongs.

It is to be noted that the jaws 1, 2, are provided with portions 13 of less width than the distance between the jaws 12 of the opposed arms 11, thus enabling the spring-transferring member to be placed accurately on the spring so that flexure of the spring, and consequent escape of the spring therefrom, cannot occur. Different sizes of spring-transferring members will be manufactured for different sizes of springs, in order that the jaws 12 may be properly spaced for receiving the spring when the spring has been compressed to its maximum, and to hold said spring in substantially its maximum contracted position, thus minimizing the tendency of the spring to flex and escape from the spring-transferring member in transferring the spring from between the jaws 1, 2, to its functioning position in the engine or elsewhere.

I claim:

1. In a tool of the character described, the combination of spring-compressing jaws, means to move one of the jaws toward the other to compress a spring therebetween,

and a spring-transferring member having opposed arms each provided with jaws to engage the opposite ends of the spring, said arms being joined together by a spring member yieldingly holding the arms toward each other.

2. In a tool of the character described, the combination of spring-compressing jaws, means to move one of the jaws toward the other to compress a spring therebetween, and a spring-transferring member having opposed arms each provided with jaws to engage the opposite ends of the spring, and a U-shape spring member connecting the arms to each other.

3. In a tool of the character described, opposed arms each having jaws to engage the opposite ends of a spring, and a spring member connecting the arms to each other.

4. In a tool of the character described, the combination of a tool body having a jaw at one end and a lug at its opposite end, a screw adjustably engaging the lug, a second jaw slidably engaging the body and loosely mounted on the screw, and a spring-transferring member having opposite arms provided with jaws to engage the opposite ends of a spring compressed between the first and second jaws.

Signed at Santa Barbara, California, this 2d day of December, 1920.

JOHN CARRICART.
